UNITED STATES PATENT OFFICE.

PAUL F. WILLIAMS, OF CHICAGO, ILLINOIS, ASSIGNOR TO G & W ELECTRIC SPECIALTY CO., OF CHICAGO, ILLINOIS, A CORPORATION OF ILLINOIS.

POTHEAD FOR ELECTRICAL CIRCUIT CONNECTERS.

Application filed August 5, 1918. Serial No. 248,305.

To all whom it may concern:

Be it known that I, PAUL F. WILLIAMS, a citizen of the United States, residing at Chicago, in the county of Cook and State 5 of Illinois, have invented a certain new and useful Improvement in Potheads for Electrical Circuit Connecters; of which the following is a full, clear, concise, and exact description, reference being had to the accompanying drawings, forming a part of 10 this specification.

My invention relates to pot heads for electrical circuit connecters.

The principal object of the invention is 15 to provide a simple and practical pot head construction.

A further object of the invention is to provide a construction by which the pot head may be interchangeably mounted either 20 upon a pole or a cross arm of a pole or upon a pipe or other upright tubular member.

A further object of the invention is to provide a simple and practical construction 25 by which the pot head body and cover may be advantageously attached to one another and the electrical connection satisfactorily made.

In the accompanying drawings Fig. 1 is 30 a side elevation of a pot head embodying my present invention;

Fig. 2 is a longitudinal section of the same;

Figs. 3 and 4 are transverse sections taken 35 on lines 3—3 and 4—4 in Fig. 2;

Fig. 5 is an elevation showing the pot head structure mounted upon a cross piece of a pole or similar device;

Fig. 6 is a cross section taken on line 40 6—6 in Fig. 5.

In the accompanying drawings I show a pot head structure consisting of a base member 1 and a top or cover member 2. The base member 1 is provided with a metallic socket 3 which is connected with a cable 4 which extends down through the lower end of said body member 1, said cable being broken away below the terminal 3 and its lower portion being omitted from the drawing for convenience of illustration. The top 2 is provided with a plug member 5 which is inserted into the socket member 3 so as to make proper electrical connection between said members 3 and 5 which thus form the cooperating contacts of the de-

vice. The plug member 5 is screw threaded upon the lower end of a screw 6 having a flange or head 7 fitting in a cavity or recess 8 in said top member 2. A terminal 9 is secured to the upper end of the screw 6 and receives the metal wire of an overhead conductor 10. This construction with the threaded member 6 fitted to the tubular plug member 5 allows the contact 5 to be secured detachably to the cap 2.

The member 3 is provided with an enlargement 11 which is exteriorly screw threaded as at 12 and fits into the threaded socket of a metal plate 13, which in turn is secured as by screws 14 to a collar or tubular member 15. Screws 16 pass through the plate 13 in a diagonal manner and engage the enlargement 11, thereby in effect locking the member 3 in position. The plate 13 covers the top of the body member 1 and thereby in effect closes it to keep out water, dirt, etc. This plate, as stated, is held in position by screws 14, of which there are several, preferably three, as shown in Fig. 3. The collar member 15 is preferably of metal and is firmly embedded and cemented in position in the top of the member 1, so as to form a firm support and holding means for the plate 13. The socket member 3 is in turn firmly held in position by means of the screws 16, of which there are also preferably three. The plug member 5 may thus be inserted into the contact socket 3 by merely placing the cap or cover 2 in position over the body part 1, a firm and secure contact thus being provided.

At the base of the member 1, I provide an improved coupling or mounting arrangement. This involves a metal collar or tubular member 17 which is firmly secured to the lower end of said member 1, as by cement 18 and 19. The lower end of this collar 17 is interiorly screw threaded as at 20 and a plug member or fitting 21 is screw threaded into the lower end 22 of said member 17. The fitting 21 substantially closes the lower end of the body member 1 and so with the top closure comprising the plate 13 and associated parts, effectively seals the contents of said body member 1, said body member 1 usually being provided with insulating compound which is distributed through said member and around the contacts and conductors therein. The fitting 21 is, however, provided with an aperture 23 through which

the cable is understood to pass. The member 21 is provided with an annular projecting lip 24 which engages the inner edge of a collar 25 which fits against the lower edge 5 of the bottom 22 of the member 17. A conduit member 26 is screw threaded into the interior of the member 25. This conduit member 26 is for the purpose of engaging and resting upon a pipe or other tubular 10 member 27 by which the pot head device is to be supported.

A device for engaging and supporting the flared end of the lead sheath of the cable is also provided, the same consisting of a 15 flat collar 28 threaded into a threaded socket 29 in the member 21 and an annular member 30 supported on the collar 28 by means of uprights 31 and a loose member 32 held to the member 30 by means of the screws 33. 20 Certain broad features of this arrangement are disclosed and claimed in my Patent No. 1,225,300, issued May 8, 1917, for connecting device for electrical conductors. A loose gland member 34 is also provided within 25 the member 21 to fit over the outer surface of the cable sheath. Packing 34^a is used in connection with this gland to make the connection with the cable water tight. Thus the arrangement is assembled by first mounting 30 the conduit member 26 on the conduit or pipe 27. The cable is then extended up through the conduit and passed through the aperture 23 in the member 21. The member 28 is threaded into the member 21 and the 35 cable sheath is flared and secured in position between the members 30 and 32. The collar 25 is then put in position and then the body member 1 is placed in position and screwed down so as to engage the member 40 21 and fit firmly upon the top of the same, thus placing the pot head 1 in proper position. The end of the cable is then connected with the contact 3 and if desired, as is usually the case, insulating compound is 45 poured into the interior of the member 1. The contact 3 is then secured in position by means of the plate 13 and screws 16. Thereupon the cap 2 is put in position, the overhead wire 10 having been first previously 50 connected with the member 9, by which it is connected electrically with the plug member 5.

The above described construction of the cable engaging means may be modified in 55 order to permit the device to be mounted upon a cross arm or other support by means of a bracket, instead of being mounted upon a pipe. This modified arrangement is shown in Figs. 5 and 6. In this arrangement the 60 members 25 and 26 are dispensed with and the member 21 is screwed into the part 22 so that the flanges 24 come against the lower surface of the part 22. The device is then mounted upon a bracket such as the bracket

36 and is held in position by means of bolts 65 37 passing upwardly through said bracket and also passing into threaded sockets 38 on the member 17. Thus the pothead may be held firmly in position and the cable passed through the member 21 and sealed 70 thereby, and the other advantages previously outlined may be obtained. The bracket 36 is preferably provided with vertical supporting portions 39 which may be screwed against a cross arm 40 or other supporting 75 member by means of bolts 41, the bracket being preferably first placed in position and then the pot head mounted upon it.

It will be understood that changes and modifications may be made without departing 80 from the spirit of the invention.

What I claim is:

1. In a pothead, a body member having a longitudinal bore and a ring member 15 permanently fitted in the bore of said body member, a plate member 13 fitted on top of and covering the ring member 15, a screw 14 passing downward through the plate member 13 and into the ring member 15 to hold said plate member in position, and a terminal member passing through the plate 85 13, said terminal member comprising an externally threaded socket provided with a smooth bore and having a threaded connection with the plate member 13, and adapted to slidably receive a second terminal member in the smooth bore.

2. In a pothead structure, the combination with a supporting upright, of a hollow body portion and means for enclosing a supporting upright comprising an upright engaging device, a collar with which said device has threaded connection, means for detachably securing said collar to the body portion, and means supported by said detachable means and lying above said upright engaging device within the body for engaging a conductor entering at the bottom of said body.

3. In a pot head structure, the combination with a supporting upright of a hollow body portion and means for enclosing said supporting upright comprising an upright engaging device, a collar with which said device has threaded connection, and means for detachably securing said collar to the body portion, said securing means comprising a collar having a flanged portion which extends into and has screw threaded connection with the lower portion of the body member.

4. In a pot head, the combination with the body member of a fitting 21 having a flange fitting inside and having screw threaded engagement with the lower end of the body member, a collar 25 having one end clamped between the body and fitting and held in position by the fitting 21 and a bracket sup-

port 26 surrounding said fitting 21 and having a threaded connection with the inside of the collar 25.

5. In a pothead, the combination with a body member having a chamber, and a cap for said body member, of a separable connector for the body member and cap comprising a plate covering and completely closing the upper end of the chamber, said plate being detachably mounted in said end, a hollow terminal member opening upward and disposed through said plate and in detachable threaded engagement therewith, and a terminal member on the cap receivable 10 15 20 25 slidably in said hollow terminal member.

6. In a pot head, the combination with a body member of a metallic fitting 17 secured to the lower portion of the body member and having an end portion 22 interiorly 20 25 screw threaded, a fitting 21 having an upwardly extending flange provided with screw threads adapted to engage the threads on the part 22, said fitting 21 also having an annularly projecting portion 24, extending laterally and adapted to fit against the bot-

tom edge of the member 22, a collar 25 having a flange adapted to fit between the projecting rim 24 and said bottom 22 and a member 26 having a threaded upper end fitted within the collar 25, which is internally threaded to receive it. 30

7. In a pot head, the combination with a body member of a metallic fitting 17 secured to the lower portion of the body member and having an end portion 22 interiorly 35 screw threaded, a fitting 21 having an upwardly extending flange provided with screw threads adapted to engage the threads on the part 22, said fitting 21 also having an annularly projecting portion 24, extending 40 laterally and adapted to fit against the bottom edge of the member 22, a collar 25 having a flange adapted to fit between the projecting rim 24 and said bottom 22, and a bracket 26 having its upper end provided 45 with screw threads to fit into the collar 25.

In witness whereof, I hereunto subscribe my name this 29th day of June, A. D. 1918.

PAUL F. WILLIAMS.
